FOLDABLE BOAT

Benjamin F. Randrup, Brisbane, Calif.

Application May 22, 1944, Serial No. 536,811

5 Claims. (Cl. 9—2)

1

This invention relates to improvements in folding boats.

An object of my invention is to provide a foldable boat embodying a construction capable of being readily collapsed and folded into a compact form for convenience in handling, storage or transportation.

Another object of my invention is to provide a foldable boat having longitudinally disposed bottom and side members which are articulately connected along their contiguous edges, whereby the parts may be readily unfolded from a collapsed form into a rigid boat structure wherein the parts are firmly secured in extended positions and so locked that there is no danger of accidental collapse.

A further object of my invention is to provide a folding or collapsible boat which, when in an assembled and operable form, provides a rigid and seaworthy structure wherein a considerable amount of material and a number of persons may be safely carried without likelihood of damage or injury from leaks, capsizing or foundering.

Other and further objects of my invention will be pointed out hereinafter, indicated in the appended claims, or will be obvious to one skilled in the art upon an understanding of the present disclosure. For the purpose of this application, I have elected to show herein certain forms and details of a folding boat representative of my invention; it is to be understood, however, that the embodiment of my invention herein shown and described is for the purpose of illustration only, and that therefore it is not to be regarded as exhaustive of the variations of the invention, nor is it to be given an interpretation such as might have the effect of limiting the claims short of the true and most comprehensive scope of the invention in the art.

In the accompanying drawings:

Fig. 1 is a side elevation of a folding or collapsible boat embodying the preferred principles of my invention;

Fig. 2 is a plan view of the same;

Fig. 3 is an end view of the same;

Fig. 4 is an enlarged sectional view taken on the line 4—4 of Fig. 1, showing the manner in which the bottom and side members are fastened together;

Fig. 5 is an enlarged sectional view taken on the line 5—5 of Fig. 2, showing the manner in which the bottom of the boat is constructed;

Fig. 6 is an enlarged side elevation of one of the oar locks;

2

Fig. 7 is a sectional view taken on the line 7—7 of Fig. 6;

Fig. 8 is an enlarged detail section showing the manner in which the end members are secured to the sides of the boat;

Fig. 9 is an enlarged sectional view taken on the line 9—9 of Fig. 2;

Fig. 10 is an enlarged sectional view taken on the line 10—10 of Fig. 2;

Fig. 11 is an enlarged sectional view taken on the line 11—11 of Fig. 2;

Fig. 12 is an enlarged side elevation of one of the hinges employed in connecting certain parts of the boat together and maintaining them in foldable relationship;

Fig. 13 is a sectional view showing the boat in a collapsed or folded form;

Fig. 14 is a diagrammatic plan view showing a number of the boats connected end to end to form a supporting structure for a bridge; and

Fig. 15 is a side elevational view of the connected boats shown in Fig. 14.

Referring to the drawings, the numerals 1 and 2 designate two elongated bottom members which are flexibly connected together along their adjacent longitudinal side edges by an intervening strip 3 of waterproof fabric, such as canvas. The waterproof strip 3 is secured to the bottom members at their upper sides by means of nailed, glued, or otherwise suitably secured battens 4. Overlying the strip 3 is a rigid longitudinal member 5. Secured to and underlying the strip 3 is a rigid longitudinally disposed member 6 which is normally engaged at its opposite side edges by the lower inner side edges of the bottom members 1 and 2 (see Fig. 5). Secured to and underlying the member 6 is a lower longitudinally disposed member 7 which normally extends across the longitudinal space separating the inner edges of the bottom members. The lower member 7 provides a support for the inner edges of the bottom members 1 and 2 and at the same time it forms rigid protecting means for normally preventing damage to the keel area of the boat when landings are made. The bottom members 1 and 2 are made preferably from flat panels of plywood or other suitable material, and each is substantially rectangular in shape. When the boat is unfolded and set up and the various parts are in assembled cooperating positions, the bottom members 1 and 2 are slightly inclined in opposite directions.

Flexibly connected to the outer edges of the bottom members 1 and 2, respectively, are elongated side members 8 and 9. The adjacent edges 55 of the bottom and side members are connected

together by waterproof strips 10 of canvas or other suitable material. The flexible strips 10 are secured to the inner surfaces of the side and bottom members by nailed, glued or otherwise suitably attached battens 11. The side and bottom members when in unfolded and set up positions are arranged so that the lower edge of each side member rests on its associated bottom member. The particular battens 11 which are secured to the bottom members 1 and 2 provide abutments to prevent the lower edges of the side members from engaging with the flexible strips 10. Such a connecting means for the bottom and side members is well protected from damage from the outside and it still permits the folding of the members one upon another in a most satisfactory manner.

Hinged as at 12 to the bottom member 2 is a centrally disposed member 13 (see Fig. 5) which normally overlies the longitudinal member 5 and provides a rigid floor piece for protecting the flexible connecting strip 3 against damage from within.

The stern and bow of the boat are constructed substantially alike and each comprises a flexible end member 14 of waterproof material such as canvas which is somewhat rectangular in shape. The lateral and lower edges of the end members 14 are secured to the bottom members 1 and 2 and to the side members 8 and 9 by spaced glued or nailed battens 14' or other suitable means which will prevent water from entering where the end members engage with the side and bottom members.

Secured as by universal hinges 15 (see Fig. 11) to the opposite ends of the bottom members 1 and 2, respectively, are rigid end panels 16 and 17 which are each of sufficient length to extend across an end of the boat. When the boat is in a set up position the end panels 16 and 17 are lodged at their opposite ends between the battens 14' which are secured to the side members 8 and 9. (See Fig. 8.) The hinges 15 are so constructed and arranged as to permit the end panels 16 and 17 to be removed from engaging positions between the spaced battens 14' without detachment from the bottom members 1 and 2 when the boat is to be collapsed and folded. The end panels 16 and 17 are normally positioned in lengthwise engagement with each other. They provide rigid stiffening members for maintaining the bottom and side members in their unfolded respective normal positions, and at the same time they maintain the flexible end members 14 in taut, protected positions. The end panels 16 and 17 are adapted to fold against the bottom members 1 and 2, respectively, when the boat is collapsed. When extended across the ends of the boat, the end panels 16 and 17 are secured together at one or more points by bolts 18 or other suitable means.

Extending across the interior of the boat in engagement with the side members are pairs of angular frame members 20, which form rigid U-shaped ribs or frames for maintaining the side and bottom members in extended positions. The angular frame members are connected to the bottom members as by universal hinges 21 (see Figs. 9 and 12) which permit the folding of the said frame members against the bottom members. The upwardly disposed parts of the frame members 20 are normally lodged between spaced strips 22 secured to the inside surface of the side members 8 and 9. The lower portions of the frame members of each pair extend across the bottom of

the boat alongside one another. Hinged as at 23 to the lower portions of the frame members 20 are horizontal seats 24 which extend across the interior of the boat and are supported at their opposite ends by strips 25 secured to the side members 8 and 9. When the boat is being set up it becomes necessary to exert an inner pull upon the upper edges of the side members 8 and 9 in order to bring the side and bottom members into their proper relative positions as well as into firm engagement with the U-shaped ribs. The preferred means used to accomplish this result comprises a number of three-piece clamps 26 (see Fig. 9) of the kind employing a principle commonly used in trunk latches to secure the lid to the main body. The clamps are mounted on the upper ends of the angular frame members 20, and each clamp is adapted to engage with an upwardly disposed member 27 secured to the upper edges of the side members 8 and 9, and by swinging the lever members of the clamps inwardly, the side members 8 and 9 at their upper edges are drawn toward each other and into firm engagement with the frame members 20, thereby forming a rigid construction throughout the length of the boat.

Secured as by a universal hinge 28 (see Fig. 10) to the longitudinal member 5 at each end of the boat is a centrally disposed brace 29 which extends longitudinally to the end panel 17. The braces 29 are each normally disposed in a vertical plane and an end thereof is secured to the end panels 16 and 17 by a bracket 29' and one of the same bolts 18 which normally holds the said panels in engaging relationship. Each brace 29 provides a rigid reenforcing structure for an end of the boat, and if desired it may serve as a support for an outboard motor or other device.

At opposite sides of the boat, on the upper edges of the side members 8 and 9 are mounted oar locks 30 which are adapted to drop from an upwardly extending position to one wherein they are positioned against the said side members (see Fig. 7). The oar locks are each provided with an upper opening for the insertion of an oar and with a lower opening for the engagement of a bracket 31 which serves as means for securing the oar lock to the side member.

At opposite sides of the boat near the two ends thereof are arranged four foldable buoyant members 32 which are suitably secured to the upper areas of the side members 8 and 9. (See Figs. 2, 3 and 11.) Each of the buoyant members is preferably provided with a hinged side 33, canvas ends 33' and a pivoted top 34 which has a hinged door 35. The side 33 of the buoyant member is movably connected at its lower end by a waterproof strip to a side member 9, and a similar hinge connection is provided between the top 34 and the side 33 as well as between the door 35 and the side member. The hinged door is provided with a latch 36 for holding the door and the top 34 in connected relationship. The interior of each buoyant member has an air chamber which is adapted to provide suitable buoyancy to prevent the capsizing of the boat in rough waters. When folded the door drops downwardly against the side member 9, the top 34 drops downwardly against the inside surface of 33, and the latter with the canvas ends 33' tucked inwardly is positioned in close proximity to the said member.

As shown in Figs. 14 and 15, the ends of several boats may be connected as by interlocking means 37 to provide an elongated supporting

structure for a pontoon bridge. When so connected together, the boats provide a semi-rigid structure capable of supporting a considerable weight.

The universal hinges 15, 21 and 28 are each provided, as shown in Fig. 12, with a plate 38, a looped member 39 on said plate, a pin 40 connected to the looped member, and a second plate 41 having an eye or opening within which the pin is rotatably mounted and held. The free movement of the pin 40 with respect to the looped member 39, and the free movement of the second plate 41 about the pin 40 permits the members to which the plates are secured to assume various positions with respect to one another. Thus the frame members 20, the end members 16 and 17 and the braces 29 are respectively held in a connected position with respect to bottom members 1 and 2 and the longitudinal member 5, both when the boat is in a set up position and when it is folded.

When the boat is to be collapsed for convenience in carrying, storage or handling, the clamps 26 and the bolts 18 are first disconnected, following which the frame members 20 making up the U-shaped ribs, the braces 29 and end panels 16 and 17 are folded against the bottom members 1 and 2. The buoyant members 32 are collapsed and positioned alongside the side members 8 and 9. The seats 24, previous to the folding of the frame members 20, are folded against the latter. The side members 1 and 2 are swung inwardly against their associated bottom members 8 and 9, and each of the latter, together with the aforementioned parts connected thereto, are then folded upwardly toward each other. The flexible end members 14 are tucked inwardly between the adjacent side members, and a suitable cord or other means is then extended around the folded structure to maintain the various parts of the boat in a collapsed form. Owing to the novel manner in which the parts are arranged and connected together, the time required to assemble the structure into an operable boat is but a few minutes.

Having described my invention, what I claim is:

1. In a collapsible boat, a pair of elongated bottom members flexibly connected longitudinally along adjacent side edges, two elongated side members flexibly connected to the outwardly disposed longitudinal edges of the bottom members, the said side members each being arranged to fold upon its associated bottom member, foldable end members pivotally connected to and foldable upon the bottom members, the said end members being arranged in pairs and each pair being positioned to close an end of the boat, and a plurality of pairs of rigid frame members pivotally connected to and folded upon the bottom members and normally interposed between the side and bottom members for maintaining them in unfolded positions, the pairs of rigid frame members each comprising two angular members connected to the bottom members and arranged to engage with the side members, and seats pivot-

ally connected to and foldable upon the frame members.

2. In a collapsible boat, a pair of elongated bottom members flexibly connected together longitudinally along adjacent side edges, two elongated side members flexibly connected to the outwardly disposed longitudinal edges of the bottom members, the side members each being arranged to fold upon its associated bottom member, foldable end members pivotally connected to and foldable upon the bottom members, the said end members being arranged in pairs and each pair being positioned to close an end of the boat, rigid frame members connected to and foldable upon the bottom members and normally interposed between the side members for maintaining them in separated positions, and seats pivotally connected to the frame members and arranged to fold thereupon.

3. In a collapsible boat, means for connecting an elongated side member to an elongated bottom member comprising a flexible strip interposed between adjacent longitudinal edges of the side and bottom members, and longitudinally disposed battens securing the strip to the side and bottom members, the battens and flexible strip being arranged on the inside of the boat and one of the battens being positioned to provide an abutment for the longitudinal edge of the side member when the boat is in an unfolded operative position.

4. In a collapsible boat having flexibly connected elongated side and bottom members, means for connecting a longitudinal side edge of a bottom member with an adjacent longitudinal side edge of a side member, comprising a flexible strip arranged interiorly and disposed between the adjacent longitudinal edges of the side and bottom members, two longitudinal battens engaging with the lateral longitudinal edges of the strip, one being secured to the bottom member and the other to the side member, the particular batten secured to the bottom member being arranged to engage with the aforesaid longitudinal edge of the side member when the boat is in an unfolded operative position, whereby lateral strains on the strip are reduced and contact therewith from the outside is avoided.

5. In a collapsible boat comprising longitudinally connected side and bottom members arranged for folding one upon another, the side members being arranged in upstanding positions with respect to the bottom members with their lower longitudinal edges resting on the bottom members, flexible strips positioned interiorly of the boat and arranged to form a water-tight flexible joint between the adjacent longitudinal edges of the bottom and the side members, and longitudinally disposed battens positioned interiorly for securing the flexible strip to the bottom and side members, the said battens securing the strips to the bottom members being arranged to engage with the lower edges of the side members, whereby the said side members are prevented from shifting beyond certain points and thereby exerting strains in the flexible members.

BENJAMIN F. RANDRUP.
